MOTOR BIKE FRAME

Glen R. Shaw, 504 East 29th South,
Ogden, Utah 84403

Filed Mar. 12, 1969, Ser. No. 16,219

Term of patent 14 years

Int. Cl. D12—11

U.S. Cl. D90—8

FIG. 2

FIG. 1

FIG. 3

FIG. 4

FIGURE 1 is a side elevation view of a motor bike frame embodying my new design;

FIGURE 2 is a top plan view of the motor bike frame of FIGURE 1;

FIGURE 3 is a front view of the motor bike frame of FIGURE 1; and

FIGURE 4 is a rear view of the motor bike frame of FIGURE 1.

I claim:

The ornamental design for a motor bike frame, substantially as shown.
